UNITED STATES PATENT OFFICE.

LYNN A. WILLIAMS, OF EVANSTON, ILLINOIS.

MAGNETO-MACHINE.

1,117,616.

Specification of Letters Patent.

Patented Nov. 17, 1914.

Application filed November 17, 1913. Serial No. 801,374.

To all whom it may concern:

Be it known that I, LYNN A. WILLIAMS, a citizen of the United States, residing at Evanston, in the county of Cook and State of Illinois, have invented certain new and useful Improvements in Magneto-Machines, of which the following is a full, clear, concise, and exact description, reference being had to the accompanying drawings, forming a part of this specification.

My invention relates to magneto machines, and particularly to that class of magneto machines employed in connection with make-and-break ignition devices to produce the ignition sparks or arcs necessary for internal combustion engine operation. The magneto is preferably of that type comprising a solid metal rotor movable in one direction by an engine-driven actuating device, and returned quickly to normal position by springs when released from said actuator to cause a rapid change in the magnetic flux through the energizing windings of the magneto machine to cause the flow of the spark-producing current. While the exact details of the magneto machine *per se* are not particularly important, in so far as the present invention is concerned, it is essential that the movable element thereof be operable by an engine-driven actuator and provided with means for quickly returning it to normal position by spring action, as set forth.

One of the objects of the present invention is to provide a lever whereby the movable element of the rotor of the magneto by one stroke of the lever may be manually moved from normal position, released and then quickly returned to normal position by the springs to cause the flow of current and so create a spark to ignite the initial or starting charge within the cylinder of the internal combustion engine with which the magneto is associated in order that the engine may be started without cranking. The make-and-break ignition devices are, of course, operated simultaneously with the operation of the magneto machine to permit the passing of the spark at the proper time. The manually-operated lever just referred to is conformed and proportioned to secure the maximum mechanical advantage and is adapted to be used as a gage for adjusting the magneto and so that the same may be operated at the necessary time during the engine cycle. These and other features of my invention are fully set forth in the fol-

lowing description and are illustrated in the accompanying drawings, in which—

Figure 1 is a front view of the mechanism of my invention; Fig. 2 is a rear view thereof, certain parts being illustrated in section; Fig. 3 is a detail view illustrating the position of the hand-operated starting lever immediately before the rotor of the magneto machine is released therefrom, and Fig. 4 is a detail view showing the hand-operated starting lever used as a gage.

Similar reference numerals refer to similar parts throughout the several views.

Referring to the drawings, I have shown the framework of the magneto machine at 5, said magneto being provided with the field magnets 6 mounted in the framework 5. The said field magnets are provided with suitable pole-pieces (not shown) located in the framework 5, and movable between said pole-pieces is a rotor (not shown), said rotor being rigidly attached to a shaft 7. The rotor referred to is preferably in the form of a solid metal inductor adapted when operated to cause a rapid change in the magnetic flux passing through generating windings mounted upon the pole-pieces. These last-mentioned features of magneto machine construction are now well known to those skilled in the art, so it will be unnecessary for me to go into any elaborate description of the same at this time.

Keyed or otherwise rigidly secured upon the shaft 7 is a yoke 8, said yoke being bent at its ends to form the portions 9 substantially parallel to the axis of the shaft 7. Acting between the portions 9 of the yoke 8 and pins 10 mounted in brackets supported by the framework of the machine are the helical springs 11 which normally retain the yoke 8 in the position shown in Fig. 1 of the drawings. Mounted upon the pins 10 and the portions 9 of the yoke are suitable rollers 12 engaged by the ends of the helical springs 11.

Rigidly mounted upon the rear end of the shaft 7 is an operating arm 13 arranged to be operated by an engine-driven actuating rod 14. It will be seen that the actuating rod 14 passes over a roller 15 and that therefore the position of the roller 15 will determine at what point in the engine cycle the arm 13 will be released from the engine-driven actuating rod 14.

The magneto machine may, if desired, be mounted upon a bracket 16 arranged to be

secured to the side of an engine cylinder. The present invention is not particularly concerned with the details of the bracket 16, so the same is merely shown partially in section and partially in elevation in Fig. 2 of the drawings.

At 17 in Fig. 2 I have illustrated in section a shaft upon which in practice is rigidly mounted the movable contact of a make-and-break ignition device. I have not thought it necessary to illustrate the make-and-break contacts because these devices are well known to those skilled in the art. It will suffice to say that turning the shaft 17 effects the closing or separation of said contacts. Rigidly mounted upon the shaft 17 is an arm 18, and acting between said arm and the bracket 16 is a helical spring 19 which normally tends to move the arm 18 and shaft 17 in a clockwise direction (Fig. 2). Threaded into the lower end of the arm 18 is a screw 20 which normally abuts against an arm 21 formed integral with the arm 13 mounted upon the shaft 7.

Mounted upon the right hand one of the pins 10 (Fig. 1) is a manually-operated lever 22 rounded to a point at 23. It will be seen that the lever 22 is provided with two apertures illustrated at 24 and 25, the pin 10 being disposed in the aperture 24 when the lever 22 is used as a starting lever and the said pin 10 being disposed in the aperture 25 when the lever is utilized as a gage.

Assuming the piston within the engine cylinder with which the magneto machine just described is associated to be in proper position and the cylinder to contain a suitable combustible charge; the lever 22 is in the position shown in full lines in Fig. 1 of the drawings and the make-and-break contacts within the engine cylinder are closed. The long arm of the lever is then depressed, moving the yoke 8 to the position shown in Fig. 3 of the drawings. It will be seen that it is necessary to give the lever 22 but a single thrust, as the portion 9 of the yoke engaged by the lever will slip off the pointed end of the lever when the lever has reached a certain position. As soon as the yoke is released from the lever, the helical springs 11 serve to quickly return the yoke and rotor to normal position, thus causing a rapid change in the magnetic flux through the energizing windings of the magneto machine and causing the flow of ignition current.

Referring to Fig. 2 of the drawings, it will be seen that when the lever 22 is operated to move the yoke to the position shown in Fig. 3, the arm 21 rigidly mounted on the shaft 7 will be moved in a clockwise direction (Fig. 2), and out of engagement with the screw 20 carried by the arm 18, the spring 19 tending to hold the movable contact mounted on the shaft 17 in engagement 65 with its associated stationary contact.

When the yoke is released from the lever the springs 11 not only carry the yoke and parts fixed relatively thereto to normal position, but carry them past normal position, whereupon the arm 21 acts as a hammer to engage the screw 20 serving as an anvil to move the arm 18 in contra-clockwise direction (Fig. 2), against the tension of the spring 19 to separate the contacts within the engine cylinder and so cause the passing of a spark to ignite the combustible charge within the engine cylinder.

The engine, having started as a result of the explosion of the charge caused by operating the lever 22, the magneto machine is now operated at the proper time in the engine cycle by means of the engine-driven actuating rod 14, which once in every engine cycle moves the arm 13 and parts fixed relatively thereto in a clockwise direction (Fig. 2), the said arm 13 being released from said actuating rod at the proper time and returned quickly to a normal position by the helical springs 11. The sparking contacts are, of course, operated when the magneto machine is being driven from the engine in identically the same manner that they are operated when the magneto is operated by the starting lever 22. When the lever 22 is not in use it may be removed from position 95 upon the pin 10 which supports it, or it may be permitted to assume the position illustrated in dotted lines in Fig. 1.

The roller 15 which causes the engine-driven actuating rod 14 to be disengaged from the arm 13 at the proper time is mounted on a spindle 26 fixed to a disk 27, and also fixed to said disk is a shaft or spindle 28 mounted in a block 29 supported by the bracket 16. The shaft 26 is disposed eccentric to the shaft 28 so that by adjusting the handle 30 mounted upon the spindle 28, the time in the engine cycle at which the arm 13 is released from the engine actuating rod 14 may be determined. Thus the passing of the spark in the engine cylinder may be advanced or retarded within certain limits. The handle 30 is provided with a flat spring 31 arranged to engage in suitable notches in a sector 32 formed integral with the block 29.

It will be seen that the block 29 is secured to the bracket 16 by means of screws or bolts 33 passing through an elongated slot 34 in said block. The time in the engine cycle at which the spark passes is primarily determined by positioning the block 29 relative to the machine frame-work. The spark is advanced or retarded within certain limits by manipulating the handle 30. When it is desirable to adjust the position of the block 29 with respect to the other parts of the magneto machine, the lever 22 is utilized as a gage, the pin 10 at the right hand side of the machine (Fig. 1) being disposed in the aperture 25 of the lever. The pointed end 130

of the lever is then depressed to move the yoke 8 to the position shown in Fig. 4, and this position is the one at which it is desirable to release the rotor from its actuating member during the operation of the magneto machine, regardless of whether said operating lever is the lever 22 or the engine-driven actuating rod 14. It will be seen that the yoke is securely locked in the position shown in Fig. 4 when the lever 22 is utilized as a gage, and the position of the block 29 may be readily adjusted in order that the engine-driven actuating rod 14 may be released from the arm 13 at exactly the proper time in the engine cycle.

It will be seen that the lever 22 is so rounded at 23 that when the said lever is used as a starting lever one stroke of said lever is sufficient to operate and release the yoke and that the operation of the said yoke is accomplished by means of a minimum amount of effort. The gage end of the lever serves as a handle when the lever 22 is utilized for operating the magneto machine to produce the starting spark. It will be understood that the lever 22 is utilized as a gage very rarely and that when the lever is utilized as a gage and the yoke is locked in the position shown in Fig. 4 it is necessary to withdraw the lever 22 from the pin 10 upon which it is mounted to release the yoke.

Having thus described my invention, what I claim as new and desire to secure by Letters Patent of the United States is:

35 1. In combination, a magneto machine comprising a framework and a rotor, an engine-driven actuator for moving the rotor in one direction and automatically releasable from said rotor, springs for quickly moving the 40 rotor in the opposite direction when released from said actuator, a manually-operated lever adapted on one stroke thereof to move the rotor in the direction in which said rotor is moved by the engine-driven actuator and 45 to release the rotor, and a pin fixed relatively to said rotor, said hand-operated lever com-

prising an operating arm adapted to engage said pin, said lever arm being rounded to a point and said lever being pivoted to a stationary part of the machine framework. 50

2. In combination, a magneto machine comprising a framework and a rotor, an engine-driven actuator for moving the same in one direction and automatically releasable from said rotor, mechanism for quickly moving 55 the rotor in the opposite direction when released from said actuator, and a manually-operated lever adapted on one stroke thereof to move the rotor in the direction in which it is moved by the engine-driven actuator 60 and to release said rotor, said rotor comprising an operating arm, and said lever comprising a portion adapted to engage said operating arm, the operating arm engaging portion of said lever being rounded to a 65 point and said lever being pivoted to a stationary part of the machine framework.

3. In combination, a magneto machine comprising a framework and a rotor, an engine-driven actuator for moving the rotor in one 70 direction and automatically releasable from said rotor, a yoke fixed relatively to said rotor, springs attached to said yoke adapted to quickly move the rotor to normal position when the rotor is released from said actuator, and a manually-operated lever adapted on one stroke thereof to move the rotor in the direction in which it is moved by the engine-driven actuator and to release the 75 rotor, said lever comprising a portion adapted to engage said yoke, said portion being rounded to a point and said lever being pivoted to a stationary part of the machine framework.

In witness whereof, I hereunto subscribe 85 my name this 12th day of November, A. D., 1913.

LYNN A. WILLIAMS.
